CLAIM

The ornamental design for a ratchet, as shown and described.

DESCRIPTION

FIG. 1 is a perspective view of a ratchet, according to an embodiment of the invention;
FIG. 2 is a front end view of the ratchet of FIG. 1;
FIG. 3 is a rear end view of the ratchet of FIG. 1;
FIG. 4 is a right side view of the ratchet of FIG. 1;
FIG. 5 is a left side view of the ratchet of FIG. 1;
FIG. 6 is a top side view of the ratchet of FIG. 1;
FIG. 7 is a bottom side view of the ratchet of FIG. 1;
FIG. 8 is a perspective view of a ratchet, according to another embodiment of the invention;
FIG. 9 is a front end view of the ratchet of FIG. 8;
FIG. 10 is a rear end view of the ratchet of FIG. 8;
FIG. 11 is a right side view of the ratchet of FIG. 8;
FIG. 12 is a left side view of the ratchet of FIG. 8;
FIG. 13 is a top side view of the ratchet of FIG. 8; and,
FIG. 14 is a bottom side view of the ratchet of FIG. 8.
The dashed broken lines are for the purpose of illustrating portions of the ratchet and form no part of the claimed design.
